UNITED STATES PATENT OFFICE.

HARVEY E. BLOOMER, OF MILWAUKEE, WISCONSIN, ASSIGNOR TO P. & B. MFG. CO., OF MILWAUKEE, WISCONSIN.

ELECTRIC HEATING-PAD.

1,142,393.

Specification of Letters Patent.

Patented June 8, 1915.

Application filed September 8, 1914. Serial No. 860,656.

To all whom it may concern:

Be it known that I, HARVEY E. BLOOMER, a citizen of the United States, and resident of Milwaukee, in the county of Milwaukee, 5 and State of Wisconsin, have invented certain new and useful Improvements in Electric Heating-Pads; and I do hereby declare that the following is a full, clear, and exact description thereof.

10 My invention refers to electric heating-pads and has for its object to provide a simple, economical and effective means for securing the resistance conductor to the flexible non-conducting body sheet, which 15 sheet may be of any suitable fabric or analogous material.

The specific object of my invention is to utilize the metallic conductor strand (either jacketed with insulation or bare) as a sewing 20 element in itself, whereby the resistance conductor is in stitched union with the body, the operation being effected either by stitching the conductor with a hand needle or a sewing machine, under which latter 25 conditions the bobbin thread or needle thread may be conductors or one of the threads may be of cotton or analogous material. It is understood that when the conductor thread is fed by a machine in a sewing 30 operation, it may be interlocked with a bottom thread to form any style of stitch or vice versa. By the above arrangement it is apparent that the resistance conductor so attached to the body of the pad will be 35 quickly affixed thereto with a maximum amount of surface or length of conductor in proportion to a minimum space.

Another object of my invention is to provide a jacket for the conductor-carrying 40 body, which jacket is impervious to moisture and is stitched at its edges to the body.

A further object of my invention is to protect the terminal edges of the resistance conductor by lap-folding and securing the 45 corner edges of the pad, whereby strain is relieved at the point of connecting the feed wires and resistance conductor wires.

With the above and other minor objects in view my invention consists in certain peculiarities of construction and combination of parts as set forth hereinafter with reference 50 to the accompanying drawings and subsequently claimed.

In the drawings Figure 1 represents a 55 face view of a heating-pad embodying the

features of my invention with parts broken away and removed to more clearly illustrate the details of construction, and Fig. 2, a magnified longitudinal sectional elevation of a portion of the pad showing the arrangement of stitching the conductor wire to the body sheet.

Referring by characters to the drawings, 60 1 represents a body sheet that is made of canvas or other suitable ductile non-conducting material. As best shown in the plan view the resistance conductor comprising a wire strand 2 is affixed to the body sheet by stitching said conductor to the same in the form of open parallel loops A, whereby 65 the conductor strand is quilted back and forth an indefinite number of times to provide the necessary length of resistance. The loose ends 2' of the continuous conductor are connected to feed wires 3, 3', in any 70 suitable manner, whereby the electric circuit through the pad is effected.

As best shown in Fig. 2 of the exemplification of my invention, the resistance strand 2 is fed from a needle in a stitching operation and is interlocked by a shuttle thread 4, 80 which shuttle thread may be cotton, silk or other suitable material, or both threads may be metallic forming non-resistance conductors.

It is also within the scope of my invention to insulate the metallic wire strands by covering the same with a suitable jacket material.

It should be distinctly understood that, 90 while I have shown a form of stitch, whereby the conductor strand is sewed to the body sheet, I may, without departing from the spirit of my invention, vary the form of stitch indefinitely, the essential element being that the said resistance strand forms a sewing element in itself and, by employing the strand as a sewing element, it is obvious that the pad can be cheaply manufactured with great speed and when completed, its 95 utility and lasting qualities are proportionately greater, due to the fact that in stitching the strand a greater number of feet of resistance conductor in a given length is obtained than in such heating-pads 100 wherein the conductor is laid thereon and secured in any ordinary manner.

In order to complete the pad after the stitching has been effected, the body sheet 1 has fitted to its opposite faces sheets of 105

- material 5 that are impervious to moisture and may be composed of oiled silk or other suitable fabric. This jacket facing is of approximately the same size as the pad and the edges of the jacket material are stitched to the corresponding edges of the body sheet, whereby the resistance conductor is protected. In order to finish the pad, it is preferable to cement or otherwise secure to the outer surfaces of the jacket sheets some soft material 6, such as canton flannel or analogous downy substance, whereby the pad when placed in direct contact with the body will relieve harshness.
- 15 It is also manifest that I may, without departing from the spirit of my invention, sew the resistance conductor to the body sheet in any desired arrangement other than that illustrated as, for example, should the 20 body strand be provided with an insulated jacket it might be quilted back and forth in any design to accomplish the same result.

I claim:

1. An electric heating-pad comprising a 25 flexible body sheet of non-conducting material, a wire resistance conductor constituting a sewing element in itself in stitched union with the body sheet, waterproof jacket

sheets affixed over the opposite faces of the body sheet to conceal and protect the resistance conductor, the said waterproof jacket sheets being stitched together through the edges of the body sheet, and terminal wires connecting the ends of the wire resistance conductor, the same being extended 35 beyond the jacket.

2. An electric heating-pad comprising a flexible body sheet of non-conducting material, a resistance conductor wire constituting a sewing element in itself in stitched 40 union with the body sheet having end terminals projecting therefrom, a jacket of waterproof material fitted over the body sheet, feed wires connected to the end terminals of the resistance conductor, and 45 means for securing folds of the pad over the coupling connections between the resistance conductor and feed wires.

In testimony that I claim the foregoing I have hereunto set my hand at Milwaukee 50 in the county of Milwaukee and State of Wisconsin in the presence of two witnesses.

HARVEY E. BLOOMER.
